CALIFORNIA

BOTTLE STOPPER AND FLASK CONNECTER

Application filed August 29, 1931. Serial No. 560,072.

Our invention relates to closures, with special reference to rubber stoppers for bottles, and is directed particularly to a construction that may be incorporated in a bottle stopper 5 as such, or in a flask connector of a type commonly employed in chemical laboratories and in medical practice.

The primary object of our invention is to provide a device combining exceptional 10 structural provisions for sterilization with maximum efficiency as a mechanical seal.

In chemical work, a stopper or flask connector is required from which the last trace of any chemical may be readily removed. 15 Any inaccessible surface offers serious difficulties. In medical practice, the necessity for absolute sterilization of such apparatus as that required for giving hypodermoclysis and intravenous therapy, magnifies the importance of providing fixtures free from 20 pockets, recesses, or concealed surfaces for the accumulative trapping of material.

Broadly described, our invention comprises a rubber plug adapted to be inserted in the 25 mouth of a bottle or flask, the plug having an integral rubber skirt that rolls outward to embrace the neck of the bottle. The skirt has an annular flange which engages the rim flange or bead of the bottle. Preferably, the 30 skirt is constructed to embrace the bottle neck with a suction or vacuum grip.

Further features and advantages of our invention are incorporated in the detailed 35 description which follows. This description is to be considered with the drawings, in which:

Fig. 1 is a side elevation of the detached tube connector;

Fig. 2 is a central, vertical, transverse section of Fig. 1;

Fig. 3 is a side elevation of the flask connector assembled to a flask;

Fig. 4 is a central, transverse, vertical section of the connector in the attached position shown in Fig. 3;

Fig. 5 is a similar view of a modified form of flask connector;

Fig. 6 is a similar view, showing a flask connector having a vent tube projected inside the flask;

Fig. 7 is a central, vertical, transverse section of our invention constructed as a bottle stopper; and

Fig. 8 is an enlarged fragmentary similar view of our invention, showing a modification of the skirt construction.

Figs. 1 to 4 show our preferred form of flask connector. The connector comprises a rubber plug 20, and a rubber skirt 21 integral with and extending longitudinally from the 60 plug. The plug itself may be slightly tapered to facilitate insertion in the mouth of a flask 22, and preferably has a recess 23 hollowed out of its inner end. By virtue of the hollowed inner end, any pressure confined within 65 in bottle 22 tends to press the plug into frictional engagement with the interior of the flanged neck 24, as indicated by the arrows in Fig. 4.

In this specific flange connector, the plug 70 has two longitudinal passages 25 and 26 which communicate respectively with two short external conduits 27 and 28. Preferably, the conduits are of rubber molded integral with the plug, and are of suitable length for conveniently coupling tubing to convey fluid to and from flask 22.

Skirt 21 is of sufficient length to be rolled up over the rim flange 29 of the flask to a position embracing neck 24, as shown in Figs. 80 3 and 4. The diameter of the skirt relative to the plug for a given type of flask will depend upon the tension with which it is desired to have the skirt embrace the flask, and also the characteristics of the rubber composition used.

Skirt 21 is provided with two spaced annular flanges 30 and 31 which define a channel 32 that is outwardly disposed on the detached stopper shown in Fig. 2, and inwardly disposed on the attached stopper shown in Fig. 4. Inner flange 30 engages the shoulder formed by rim flange 29, when the connector is assembled to flask 22, and a slight pressure against the vertical wall 33 of the channel will cause 85 the skirt to embrace the neck of the flask with a suction grip.

Fig. 5 shows a flask connector similar to that shown in Figs. 1 to 4, the corresponding parts being indicated by corresponding num- 100

bers, but it differs in that a thickened edge or flange 34 is substituted for the two channel-defining flanges of the first described form. In the absence of a vacuum grip, this modification depends upon a friction grip and the engagement of edge 34 with the shoulder formed by rim flange 29.

Fig. 6 illustrates a flask connector also similar to the first form, shown in Figs. 1 to 4, 10 corresponding parts being given corresponding numbers, but it differs in the addition of a vent tube 35, which is integral with plug 20 and is projected into flask 22 continuous with passage 26. This form of flask connector is 15 used where it is desired to supply liquid from the flask through passage 25, in which case conduit 35, passage 26 and lower conduit 28 provide communication between the atmosphere and the space in the inverted flask above 20 the liquid level. It will be noted that the plug serves as a substantial base for supporting inwardly extending conduit 35 with relative rigidity.

The bottle stopper shown in Fig. 7 25 comprises a solid plug 36 having a skirt identical with the first form shown in Figs. 1 to 4. Corresponding parts are given corresponding numbers.

In Fig. 8, the plug 37, which may be either 30 solid for a stopper or apertured for a flask connector, is provided with a skirt 38 having a modified form of suction channel 39. In comparison with the first form, the two channel-defining flanges 40 and 41 are thinner, 35 wider, and, particularly the upper one, more divergently disposed. In such a construction, it will be noted that atmospheric pressure tends to press flanges 40 and 41 laterally against the bottle neck 24, thereby providing 40 for increased frictional engagement with the bottle.

The flask connector or stopper is assembled 45 to the flask by simply seating the plug in the mouth of the flask and rolling the skirt over the flask rim. The insertion of the plug is facilitated both by the tapering configuration of the plug and by the increased resiliency of the inner end of the plug provided by recess 23.

50 Although our device is quickly assembled to a flask, when once attached it offers exceptional resistance to displacement by pressure from within the flask. In the first place, such internal pressure acting in recess 23 tends to expand the plug against the inner peripheral wall of neck 24, thus increasing the frictional engagement of the plug itself. In the second place, the partial vacuum in 55 the channel reinforces the inherent tendency of the channel-defining flanges to grip the flask neck; especially in this true in the case of the construction shown in Fig. 8. A third factor is the engagement of the lower flange 60 of the channel with the shoulder formed by 65 the rim of the flask. Stress caused by any

tendency of the plug to slide outward is converted by virtue of the skirt bending around rim flange 29 into a substantially radially outward pull on the channel. This fact is important because the vacuum grip offers its greatest resistance to those forces acting in a plane perpendicular to the axis of the bottle neck. It is also noteworthy that the periphery of the plug is of sufficient extent longitudinally to insure strictly axial movement in yielding to pressure from within the flask. In other words, the plug is prevented from tilting laterally, and since it can move only straight outward longitudinally, stress conveyed to the skirt is evenly distributed around the periphery of the channel.

To remove our device, the outside flange of the channel is lifted outward to release the vacuum and the skirt is then rolled downward to the position shown in Figs. 1 and 2.

Further advantages of our invention may be appreciated by a comparison with the cup-shaped type of rubber closure adapted to embrace the neck of a bottle, for example, a nursing nipple, or the construction disclosed in the applicant Pottenger's application, serially numbered 500,827, filed December 8th, 1930, and entitled "Tube connector construction."

If a cup-shaped connector, or stopper, is designed for an exceptionally tight fit, attaching it to a flask may be entirely too difficult. In our instant invention, however, the plug securely seated in the mouth of the flask serves as an anchor to resist any lateral forces incidental to the assembly operation, and the rolling action of moving the skirt over the rim of the flask so facilitates the operation that a tight fitting closure may be easily handled. The difference is especially noticeable in the case of the channel construction shown in Fig. 8. It is difficult to slip such a channel over the rim of a flask without folding the outer flange under against the neck of the flask, but no such difficulty is encountered when the channel is part of a skirt adapted to be rolled over the rim.

Our instant invention is more sanitary than the usual cup-shaped construction. To be thoroughly cleansed and sterilized between operations, a cup-shaped device should be turned inside out to expose all the surfaces that contact the fluid in the flask, especially to expose crevices and flanges that may accumulate material. The precaution of turning a cup-shaped device inside out may be overlooked in the routine of laboratory or hospital work, but all such surfaces, crevices, and flanges in our device are automatically turned outward and exposed by the very act of removing it from a flask. A study of Fig. 2 reveals that all the fluid-contacting surfaces are exterior surfaces, when the device is de-

tached, except the straight, smooth and easily cleaned fluid passages.

It is to be further noted that by designing the plug to seat tightly, the fluid-contacting surface may be restricted to the inner end of the plug, a relatively small area in comparison with the fluid-contacting area of a cup-shaped device, and offering correspondingly lesser opportunity for unsterile conditions.

Our invention may be radically changed in form and construction without departing from the principles involved, and we reserve the right to all such changes and modifications as properly come within the scope of our appended claims.

Having described our invention, we claim:

1. The combination with a bottle of: a rubber plug inserted in the mouth of the bottle; 20 a rubber skirt integral with the plug and rolled over the rim of the bottle; and two spaced, divergent, annular flanges integral with the skirt embracing the bottle neck, the two flanges forming with the skirt and bottle neck a vacuum-sustaining annular space.

2. The combination with a bottle of: a rubber plug inserted in the mouth of the bottle; a rubber skirt integral with the plug 30 and rolled over the rim of the bottle; and two spaced, divergent, and relatively thin annular flanges integral with the skirt embracing the bottle neck, the two flanges forming with the skirt and bottle neck a vacuum-sustaining annular space.

3. The combination with a bottle having a rim flange, of: a rubber plug inserted in the mouth of the bottle; a rubber skirt integral with the plug and extending around 40 said rim flange; an annular flange integral with the skirt, said flange embracing the bottle neck and engaging said rim flange; and a second, spaced, annular flange integral with the skirt and embracing the bottle neck, said flanges being divergent and relatively thin, said skirt, rubber flanges and the bottle neck defining a vacuum-sustaining annular space.

4. The combination with a flask having 50 an outward extending rim flange, of a flask connector comprising: a rubber plug inserted in the mouth of the flask, said plug having two or more longitudinal passages therethrough; two or more corresponding conduits 55 continuous with said passages; a rubber skirt integral with the plug and rolled around said rim flange; an annular rubber flange integral with said skirt, said flange engaging said rim flange and embracing the neck of the flask; and a second, spaced, annular rubber 60 flange integral with said skirt and embracing the neck of the flask, said skirt and rubber flanges forming an annular channel having diverging, side walls, said channel embracing 65 the neck of the flask with a vacuum grip.

5. The combination with a bottle having an outwardly extending rim flange, of: a rubber plug inserted in the mouth of the bottle; a rubber skirt integral with the plug and rolled over the rim of the bottle; and two spaced, divergent, annular flanges integral with the skirt embracing the bottle neck, the two flanges forming with the skirt and bottle neck a vacuum-sustaining annular space, and one of said flanges engaging said rim flange 70 of the bottle.

6. The combination with a bottle having an outwardly extending rim flange, of: a rubber plug inserted in the mouth of the bottle; a rubber skirt integral with the plug 80 and rolled over the rim of the bottle; and two spaced, divergent, relatively thin, annular flanges integral with the skirt embracing the bottle neck, the two flanges forming with the skirt and bottle neck a vacuum-sustaining annular space, and one of said flanges 85 engaging said rim flange of the bottle.

In witness that we claim the foregoing, we have hereunto subscribed our names this 19th day of August, 1931.

FRANCIS M. POTTERER, JR.
EDWIN G. HOUSE.
